UNITED STATES PATENT OFFICE.

GEORGE TURINE, OF MASS CITY, MICHIGAN.

GATE-LATCH.

1,097,485.

Specification of Letters Patent.

Patented May 19, 1914.

Application filed March 19, 1912. Serial No. 684,692.

To all whom it may concern:

Be it known that I, GEORGE TURINE, a citizen of the United States, and a resident of Mass City, in the county of Ontonagan and State of Michigan, have invented certain new and useful Improvements in Gate-Latches, of which the following is a specification, reference being had to the accompanying drawings.

10 This invention relates to improvements in sliding gate latches.

The object of my invention is to provide an improved construction and arrangement of latching mechanism, whereby the gate is automatically fastened when closed and may be locked, said fastening mechanism having means whereby the same may be readily released and the gate slid back to an open position.

20 With this and other objects in view the present invention consists in the combination and arrangement of parts as will be hereinafter more fully described and finally pointed out in the appended claim, it being 25 further understood that changes in the specific structure shown and described may be made within the scope of the claim, without departing from the spirit of the invention.

In the drawing I have shown a perspective view of a sliding gate latch embodying 30 my invention.

In the drawing I have shown a fragmentary portion of a gate latch to the upper outer corner of which is secured the latch 35 supporting brackets 19, latch supporting bracket 18, having on its sides oppositely positioned laterally projecting stop lugs 19. Pivottally connected to the bracket 18 is a latch 20, comprising parallel side bars 21, 40 the outer ends of which curve upwardly and are connected by an integral cross bar 22. The inner ends of the side bars 21 are bent into the handle forming loops 23, the inner sides of which are pivotally attached to the bracket, while the outer sides thereof serve 45 as handles for operating the latch or disengaging the same from its keeper, herein-after described. The ends of the loops 23 are disposed over the lugs 19 and arranged 50 at times to contact with the same, the outer one of which supports and holds the latch in position to engage its keeper, while the inner lug serves as a stop to limit the opening movement of the latch.

55 On the latch post 6 is secured a keeper 24,

comprising a base or attaching plate 25, which is secured to the post 6 in any suitable manner and on which is formed a rectangular block 26 having its upper end beveled on its outer edge, as shown at 27, and 60 having formed in said end a rectangular notch 28, adapted to receive the cross bar 22, which when the gate is closed, rides up the inclined surface 27 of the keeper block and drops into the notch, thus fastening the 65 gate in closed position. The block 26 is braced laterally by triangular bracing webs 29, and has formed in its outer face a depression or recess 30, which is adapted to receive the upper end of the front end bar of 70 the gate. This engagement of the end of the gate with the recess 30 firmly holds the gate against lateral movement when in a closed position. On the cross bar 22 of the latch is arranged an upstanding locking loop 31, which 75 when the gate is closed and the latch in engagement with its keeper is adapted to pass between two similar locking staples 32 arranged on the attaching plate 25. When the staples 31 and staples 32 are thus brought 80 into alinement, a pad-lock may be engaged therewith and the gate thus securely locked in closed position.

By constructing a gate latch as herein shown and described, the accumulation of 85 snow will not interfere with the opening and closing of the same.

The gate latch is simple, strong, durable and inexpensive in construction, efficient and reliable in operation and can be formed in 90 any desired size for a large farm gate or a small yard gate.

From the foregoing description taken in connection with the accompanying drawings the construction and operation of the invention 95 will be readily understood without requiring a more extended explanation.

Various changes in the form, proportion and the minor details of construction may be resorted to without departing from the 100 principle or sacrificing any of the advantages of the invention as claimed.

Having thus described my said invention, what I claim as new and desire to secure by United States Letters Patent is:

A sliding gate latch including in combination, a supporting bracket having oppositely positioned stop lugs on its sides, a latch comprising parallel side bars the outer ends curving upward and connected by an inte- 110

gral cross bar, the inner ends of said lugs being bent into handle forming loops, means to pivotally connect said loops to said bracket, said loops arranged at times to contact with said lugs, and a keeper comprising an attaching base having a block with its upper end beveled and ending in a notch, said cross bar arranged to slide over said

beveled end and drop into said notch, as and in the manner set forth. 10

In testimony whereof I affix my signature, in presence of two witnesses.

GEORGE TURINE.
